UNITED STATES PATENT OFFICE

172,780

COMBINED SLIDE PROJECTOR AND
CARRYING CASE THEREFOR

Theodore S. Briskin, Chicago, Ill., and John E. Davis, Sherman Oaks, Calif., assignors to Revere Camera Company, Chicago, Ill., a corporation of Delaware

Application February 10, 1954, Serial No. 28,937

Term of patent 14 years

(Cl. D61--1)

To all whom it may concern:

Be it known that we, Theodore S. Briskin, and John E. Davis, citizens of the United States, residing at Chicago, State of Illinois, and Sherman Oaks, State of California, respectively, have invented a new, original, and ornamental Design for Combined Slide Projector and Carrying Case Therefor, of which the following is a specification, reference being had to the accompanying drawings, forming a part hereof.

Fig. 1 is a perspective view of a combined slide projector and carrying case therefor showing our design;

Fig. 2 is a plan view thereof;

Fig. 3 is an elevation view thereof of the side opposite from that shown in Fig. 1, and Fig. 4 is a rear elevation view thereof.

We claim:

The ornamental design for a combined slide projector and carrying case therefor, as shown.
